UNITED STATES PATENT OFFICE.

CASIMIR S. CHERPECK, OF CHICAGO, ILLINOIS.

VARIABLE CONDENSER.

Application filed August 26, 1922. Serial No. 584,590.

To all whom it may concern:

Be it known that I, CASIMIR S. CHERPECK, a citizen of the United States, residing at Chicago, in the county of Cook and State of Illinois, have invented certain new and useful Improvements in Variable Condensers; and I do hereby declare the following to be a full, clear, and exact description of the invention, such as will enable others skilled in the art to which it appertains to make and use the same.

This invention relates to improvements in electrical condensers, and has for one of its main objects the provision of a condenser adapted for radio work, both for sending and receiving, and which shall be of a readily variable capacity.

One of the main objects of this invention is the provision of a variable condenser especially adapted for radio work, provided with means whereby the capacity of the same may be varied through quite a wide range, and which variation shall be manually controlled so as to enable the operator to make very delicate adjustments for proper tuning and variation of wave lengths.

A further important object of this invention is the provision of a variable condenser which will be simple of construction, economically manufactured, and which is adapted to be used in connection with inductances which may be relatively crude, either connected in series or in parallel therewith, and provided with means making it capable of very fine adjustment, thereby making it serve as the finishing touch for such inductances.

Another and further important object of this invention is the provision of a variable condenser composed of a plurality of plates of metal foil or the like, separated by a dielectric of mica or other insulator, having a portion of the plates hingedly mounted relatively to the remaining plates, and provided with means whereby the distance between the plates may be readily adjusted, and rendering possible the making of very fine or delicate variations in the capacity of the instrument.

An important object of this invention is the provision of a variable condenser which shall be dust-proof, not liable to get out of order, and which can be used in any position desired without impairing its effectiveness. Further, with the improved construction of this invention, there is no possibility

of the plates contacting, thereby causing short circuits, which practically ruin the condenser, and which often occurs in the case of the ordinary aluminum air condenser now on the market.

Other and further important objects of the invention will be apparent from the disclosures in the accompanying drawings and following specification.

The invention, in a preferred form, is illustrated in the drawings and hereinafter more fully described.

In the drawings:

Fig. 1 is a vertical sectional view of the improved device of this invention.

Fig. 2 is a sectional view taken on the line 2—2 of Fig. 1, looking in the direction indicated by the arrows.

Fig. 3 is a detail view, enlarged, showing the condenser construction, as illustrated in Fig. 1.

Fig. 4 is a vertical sectional view, showing a modification of the invention.

Fig. 5 is a detail view showing still another modification.

Fig. 6 is a sectional view taken on the broken line 6—6 of Fig. 5, looking in the direction indicated.

In the drawings:

The reference numeral 10 indicates a casing for the improved variable condenser of this invention, which casing is preferably made of wood, but which obviously may be made of any other suitable insulating material. The casing 10 is rectangular in form, as shown, and is provided at its front with a metallic plate or the like 12 attached to the wooden casing 10 by means of suitable wood screws 14. Screw-threaded openings 16 are provided in the metal plate 12 and extend into the corresponding front portion of the casing 10, being provided for the reception of machine screws or the like, which are adapted to be fitted into a panel 16, upon the rear face of which the condenser of this invention may be mounted, if desired.

Loosely mounted in conjunction with the bottom of the casing 10 and extending across the interior thereof, as shown in Fig. 2, is a block 18 of wood or other suitable insulating material, which is beveled at its rear end, as shown at 20, in Fig. 1, thereby providing for a pivotal hinged movement of said plate 18 about its rear end, and in the casing 10.

As shown in Figs. 1, 2 and 3, the metallic

foil plates, and dielectric members of the condenser proper are located between movable block 18 and the bottom member of the casing 10, and consist essentially of two sheets of metallic foil, as copper or the like, 22, and between them and separating the same a good insulating dielectric 24, as mica or similar material. The metallic foil sheets 22 are attached by non-capacity cement or the like to the upper end under faces of the base of the case 10, and the hingedly movable block 18, respectively.

As shown in the figures, electrical connections are taken off from the foil or plates 22 by means of screws or bolts 26 and 28. The outer end of the bolt 26, which passes through the base of the container 10, has affixed thereto a suitable knurled knob or binding post 30 adapted for the convenient connection thereto of a conducting wire. The upper condenser plate 22 has similarly connected thereto the bolt 28, the heads of the bolts 26 and 28 being countersunk in suitable recesses in the member 10 and 18 respectively, and the metal foil being forced down into the countersunk recesses as best shown in Fig. 3 in order that a good contact will result. The end of the bolt 28 is provided with a nut 32, by means of which a leaf spring 34 is securely fastened thereto, which leaf spring 34 extends for quite a considerable width across the hingedly movable block member 18, as shown in Fig. 2, and is doubled over upon itself into a U-shape, as shown in Fig. 1, and has its upper leg spring impelled against the upper or top member of the casing 10 so as to normally maintain the plate 18 in its lowermost position and closely pressed against the bottom member of the casing 10. The spring 34 also forms a connecting means for conducting electricity to and from the upper foil or plate 22, and contact is made with said leaf spring 34 by means of a button or the like 36 forming the head of a bolt passing through the upper member of the casing 10, and having at its outer end a suitable binding post or connecting member 38.

Passing through the forward end of the hingedly movable block 18 is a bolt 40, having a nut 42 thereon, which nut 42 holds in position an angularly bent plate 44, as best shown in Figs. 1 and 2, and against which is adapted to operate the beveled or rounded end of a screw-threaded adjusting member or bolt 46, which passes through a corresponding screw-threaded bushing 48, which bushing is fixed in an opening in the front face of the casing 10, and screw-threaded or otherwise attached to the metallic plate 12. The bushing maintains the bolt 46 in desired position, which bolt is provided at its outer end with a manually operable adjusting knob 50 or the like.

It will be seen that by turning the knob 50

an inward or outward movement of the screw-threaded bolt 46 is produced through the bushing 48, which permits of a very fine adjustment of the distance between the plates 22 of the condenser, as by this means the member 18 will be moved about its rear edge or beveled face 20, as a pivot, and the distance between the metallic foil plate member 22 can be very accurately regulated and determined.

A modification of the invention is shown in Fig. 4, wherein two movable blocks 52 and 54 are provided, each one being faced with a metallic foil condenser plate member 56, and having an insulating mica or other dielectric means 58 therebetween. The blocks are connected by means of a flat leaf spring 60 fastened thereto by means of the wood screws 62, and the whole device may be in turn fixed to the back of a panel 64 or the like, by means of a screw 66. Connecting plugs 68 are provided from the metallic foil members 56, and are provided with binding posts at their outer extremities, as shown. Fixed to the outer end of the upper block 52 is an L-shaped metallic plate 70, having passing therethrough a screw-threaded bolt 72, with a knurled knob 74 on the end thereof. The inner end of the bolt 72 operates against the inclined surface of a bearing plate 76, which is affixed to the lower plate 54, so that the distance between the plates 52 and 54 may be very delicately adjusted.

Another modification of the invention is shown in Figs. 5 and 6, whereby more prompt separation of the plates 10 and 19 may be obtained by means of a cam action, as illustrated. The cam action is accomplished by means of an egg-shaped cam 78 mounted upon the end of a suitable operating member 80, having a knurled knob 82 on the outer end thereof, and which member 80 passes through a suitable opening provided in the front face of the casing 10. The cam 78 is adapted to operate against the lower face of a metallic plate or the like 84, securely affixed to the forward end of the hingedly movable block 18 by means of a bolt 86, as shown. By this construction a more prompt angular separation of the plates may be obtained, together with a consequently quicker action.

In the preferred form of the invention the metallic foil plates are approximately .002 of an inch thick, and three inches square, the mica or dielectric being approximately from .001 to .003 inches thick, and of a slightly larger dimension than that of the foil so as to prevent shorting and brush discharge. The capacity of this size condenser may be conservatively rated at .0005 micro-farads.

It will be obvious that herein is provided a very simple and effective form of variable condenser, the capacity of which may be changed at will, and which may be adjusted

so as to enable a receiving apparatus to be tuned in with practically any wave length, and provided with a very fine and delicate adjustment so that incoming signals may be 5 clearly discerned, and sending may also be accomplished at any desired wave length with this apparatus.

I am aware that many changes may be made and numerous details of construction 10 varied throughout a wide range without departing from the principles of this invention, and I therefore do not purpose limiting the patent granted hereon otherwise than as necessitated by the prior art.

15 I claim as my invention:

1. A variable condenser including a plurality of plates, a dielectric separating said plates, and means for angularly varying the distance between the plates, said means including an angularly extending portion on one plate and an adjusting pressure-exerting means engaging said portion to move the plate to which it is attached.

2. A variable condenser including a plurality of plates, a dielectric separating said plates, and means for angularly varying the distance between the plates, said means including a beveled portion on one end of a plate and adjustable pressure-exerting 25 means engaging said beveled portion.

3. In a variable condenser, a plurality of plates, a dielectric means separating said plates, a portion of said plates being mounted upon a block movable angularly about a 35 fulcrum point, means for angularly moving said block, said means including a screw-threaded adjustment, and an inclined plate upon the fulcrumed member upon which said screw-threaded adjustment is adapted 40 to operate.

4. A variable condenser including a casing, a condenser plate upon the inner face of the base of said casing, a binding post in direct 45 connection with said condenser plate, an insulating member adapted to cooperate with the base of said casing, and movable about a fulcrum point formed by the intersection of the base and one wall of the casing, a metallic foil plate fixed to said movable member, and resilient means for maintaining said member in normal position against said base.

5. A variable condenser including a casing, a condenser plate upon the inner face of the base of said casing, a binding post in direct 50 connection with said condenser plate, an insulating member adapted to cooperate

with the base of said casing, and movable about a fulcrum point formed by the intersection of the base and one wall of the casing, a metallic foil plate fixed to said movable member, resilient means for maintaining said member in normal position against said base, and manually operated means for varying the angular relation between said movable member and the base of the casing. 60

6. A variable condenser including a casing, a condenser plate upon the inner face of the base of said casing, a binding post in direct connection with said condenser plate, an insulating member adapted to cooperate with the base of said casing, and movable about a fulcrum point formed by the intersection of the base and one wall of the casing, a metallic foil plate fixed to said movable member, resilient means for maintaining said member in normal position against said base, and manually operated means for varying the angular relation between said movable member and the base of the casing, said means including a screw-threaded bolt passing through one end wall of the casing, and a beveled plate on the end of said movable member against which the end of said screw-threaded bolt is adapted to operate. 75

7. A variable condenser including a casing, a condenser plate upon the inner face of the base of said casing, a binding post in direct connection with said condenser plate, an insulating member adapted to cooperate with the base of said casing, and movable about a fulcrum point formed by the intersection of the base and one wall of the casing, a metallic foil plate fixed to said movable member, resilient means for maintaining said member in normal position against said base, an additional binding post upon the top of said casing, and a connection from said binding post to the movable plate of the condenser, said connection including the 90 aforesaid resilient means. 95

8. A variable condenser including a plurality of plates, a dielectric separating said plates, means for angularly varying the distance between the plates, and resilient means for normally maintaining the plates in full 100 capacity relation, said resilient means forming part of the electrical connection to said plates.

In testimony whereof I affix my signature.

CASIMIR S. CHERPECK.
